CLAIM

The ornamental design for an air pump, as shown and described.

DESCRIPTION

FIG. 1 is a front perspective view of the air pump showing my new design.

FIG. 2 is a front view of the air pump.

FIG. 3 is a rear view of the air pump.

FIG. 4 is a left side view of the air pump.

FIG. 5 is a right side view of the air pump.

FIG. 6 is a top view of the air pump.

FIG. 7 is a bottom view of the air pump; and,

FIG. 8 is a rear perspective view of the air pump.

Any shading and cross-hatching are not features of the design but are utilized to illustrate the surface contours of the air pump design in the drawings.

The broken lines depict portions of the air pump that form no part of the claimed design.
